(57) **CLAIM**

The ornamental design of an apparatus for holding electronic lock components, as shown and described.

DESCRIPTION

FIG. 1 is a top perspective view of an apparatus for holding electronic lock components.

FIG. 2 is a bottom perspective view thereof.

FIG. 3 is a front side perspective view thereof.

FIG. 4 is a back side perspective view thereof.

FIG. 5 is a right side view thereof; and,

FIG. 6 is a left side view thereof.

The broken lines illustrate portions of the apparatus for holding electronic lock components, which form no part of the claimed design.
